DRAW WORKS

Forrest J. Young, Los Angeles, Calif., assignor to
The National Supply Company, Pittsburgh, Pa.,
a corporation of Pennsylvania

Application April 25, 1941, Serial No. 390,318

9 Claims. (Cl. 254—187)

This invention relates to rotary drilling apparatus as used in the drilling of wells, and is more particularly directed to a drawworks of high capacity adapted for the handling of heavy loads incident to the drilling of deep wells, and which drawworks has great flexibility requisite for high speed operation.

In the drilling of wells utilizing a bit or cutter at the end of a drill string which may be many thousand feet in length, a great portion of the time of operation of the drilling rig is used up in the making up and breaking apart of the drill string for the purpose of changing cutters, drills, or the like.

A particular bit or drill may have a life of only a few hours necessitating the withdrawal of the same from the formation for replacement, resharpening or repair. The drill string is made up of sections or "stands" of drill pipe, and these sections or "stands" are in the neighborhood of 90 feet in length and are ordinarily threaded together.

In order to obtain speed of operation in making up and breaking down such long drill strings, great flexibility in speed of operation of the hoisting mechanism or drawworks is required. Without such flexibility of operation the time required for the bringing of worn or broken bit to the surface for replacement and then lowering it back into the hole, may actually exceed the time spent with the bit "on bottom."

It is therefore an object of this invention to provide a drawworks of high capacity for the handling of heavy loads for deep well drilling and providing a maximum of flexibility for high speed operation.

Another object of this invention is to provide a drawworks having a novel form of change speed transmission drive permitting the required operation of the drilling rig with greater facility and utilizing to better advantage the speed changes provided through such transmission.

Another object of this invention is to provide a drawworks of this type wherein rotation of the spooling drum and rotary machine for normal rig operations may be controlled solely by alternate actuation of two friction clutches.

Another object of this invention is to provide a drawworks including a power transmission drive controlled through the medium of a friction clutch and in which drive there is provided a single positive coupling element for selectively driving either the drawworks or the rotary machine.

Another object of this invention is to provide a drawworks wherein separate control devices are provided for the spooling or hoisting drum and the rotary machine and which control devices include means whereby the position of a positive coupling element renders only one of the control devices operative at a time.

Another object of this invention is to provide a drawworks including a friction clutch and dual control means for operating the clutch and including interlocking means whereby only one of the control means is operable at one time.

Other objects and advantages of this invention it is believed will be apparent from the following detailed description of a preferred embodiment thereof as illustrated in the accompanying drawings.

In the drawings:

Figure 1 is a diagrammatic plan view of a rotary drilling rig and illustrating the drawworks embodying my invention.

Figure 2 is an enlarged plan view partly in section thereof.

Figure 3 is a diagrammatic plan of the control means embodied in my invention.

Figure 4 is an enlarged detail view of the control valve illustrating the same as moved to a second position.

Figure 5 is an enlarged sectional elevation of the low speed lineshaft clutch embodied in my invention.

Figure 6 is a sectional elevation of the lineshaft high speed friction clutch means embodying my invention.

Figure 7 is a sectional view of a portion of the drumshaft assembly showing the arrangement of parts for selectively driving the spooling drum or the power take-off sprocket.

Figure 8 is a plan view of the hoisting drum control means embodying my invention.

Figure 9 is a sectional view taken substantially on the line 9—9 of Figure 8.

Figure 10 is a sectional view taken substantially on the line 10—10 of Figure 8.

Figure 11 is a sectional view taken substantially on the line 11—11 of Figure 9.

Figure 12 is an enlarged sectional view taken substantially on the line 12—12 of Figure 9.

Figure 13 is a sectional elevation of the control means taken on the line 13—13 of Figure 8.

Figure 14 is a plan view of the rotary machine and drumshaft selective drive control means embodied in my invention.

Figure 15 is a plan section of the structure illustrated in Figure 14.

In the preferred embodiment of my invention as illustrated in the accompanying drawings, the drilling rig includes a rotary machine A which may be of any suitable or desirable construction well understood in the art, a drawworks unit B, and an engine or motor C for driving the drawworks B and the rotary machine A through the drawworks B.

The drawworks unit B includes a drumshaft 1 driven through a transmission unit D through the medium of a pair of transmission drives 2 and 3 from the lineshaft 4 of the said transmission unit D.

The rotary machine A is driven through the medium of a transmission connection 5 selectively clutched to or unclutched from the transmission drive 2. The transmission drives 2 and 3 are respectively the high and low speed drives from the lineshaft 4 and each drive includes a friction clutch, i. e., the friction clutch 8 for the transmission drive 2 and the friction clutch 9 for the transmission drive 3.

The construction and control of the draw-works unit B is such as to enable normal hoisting and lowering operations to be controlled solely by the alternate actuation of the friction clutches 8 and 9.

In handling of extremely heavy drill strings, it is essential that during the lifting operations of such heavy drill strings that the low speed drive for the drum 11 be utilized in order to permit the transmission of a sufficient torque to the shaft 1 to carry out the lifting operations. The use of the low speed drive of course results in a very slow travel of the line reeled on the drum 11. When the load is not of such magnitude as to require the use of such a slow speed drive, it is essential, in order to carry out the rapid operation of the drilling rig, to provide for the easy change of the drive from the slow to the high speed.

Where the hoisting is being carried out at considerable depth, this requires the transmission of the maximum torque through the shaft 1 to rotate the spooling drum 11. In order to thus transmit this maximum torque, the controls are actuated so that the drive from the engine C through the transmission unit D and the lineshaft 4 thereof is through the transmission connection 3 through the friction clutch 9 to the drumshaft 1, thus enabling the heavy drill string to be raised, beginning the operation known in the art as "coming out of the hole."

When the drilling string has been raised the length of a stand, it is necessary to uncouple the stand from the drill string or to break the threaded joint. This requires operation of the rotary machine A and the breaking out of the threaded joint is accomplished by repositioning the slips in the rotary machine to support the drill string. These slips may be of the type illustrated in Figure 5 in the copending application of Forrest J. Young, Serial No. 201,349, filed April 11, 1938.

With the slips in place and supporting the weight of the drill string, the threaded joint is "broken" by use of the automatic cathead 83 in the manner well known in the art. The friction clutch 8 is then engaged to operate the drives 2 and 5 and hence cause the rotary machine to complete unscrewing of the threaded joint. The single stand is then raised free of the drill string by engaging the friction clutch 9, and is set down on one end on the derrick floor. The hoisting block is then disengaged from the stand and is allowed to fall by gravity as the line unreels from the drum 11.

It will be noted that in my construction the drum and drumshaft may turn freely without requiring rotation of any of the driving sprockets or chains upon release of the brake bands carried over the brake rims 14 and 15. When the block reaches its lowest position, the brakes are again applied and a connection is made between the block and the upper end of the drill string. The friction clutch 9 is then engaged to raise the drill string another stand so that the operations may be repeated. It will thus be apparent that the

operations required for coming out of the hole require alternate rotation of the drum 11 and operation of the rotary machine A, and these operations are effected solely by alternate actuation of the clutches 9 and 8.

In the operation of going into the hole the chain drive 2 is disconnected from the rotary drive 5 and clutched directly to the drumshaft 1. The bit is connected to the lower end of the first stand and is lowered into the hole and is held in such position by means of the slips in the rotary machine A. The block is then disconnected from the first stand. The unloaded block is then raised at high speed by engaging the friction clutch 8, thereby driving the drum 11 through the high speed drive 2.

As is customary in this art, the traveling block on reaching the upper end of a second stand is quickly connected thereto, and the stand is swung out over the rotary machine as the block continues in its upward travel. The second stand is threadedly connected with the first stand in the usual manner through the medium of the use of the cathead 13. It is then necessary to raise the drill string slightly to release the slips which support the lower section of the drill string in the rotary machine A.

In order to accomplish this, the air-operated friction clutch 9 is engaged to cause the drum to reel in a short length of cable. The slips are then removed, the clutch 9 is released, and the connected sections are allowed to descend by gravity through the rotary machine into the well hole. When the upper end of the top section approaches the rotary table, the slips are reset and the connection between the traveling block and this section is again released. The clutch 8 is again actuated to raise the empty block at high speed and the cycle is repeated. It will again be noted that the required drum rotation of this operation of going in and out of the hole is effected solely by alternate actuation of the friction clutches 8 and 9.

In order to carry out the foregoing operations and to accomplish the required speed changes, the drawworks is preferably constructed to include the drumshaft 1, cathead shaft 12, lineshaft 4, jackshaft 21 and driveshaft 22. Each of these shafts is supported by a common frame illustrated at 23 (Figure 2) by suitably spaced bearings.

The driveshaft 22 is driven from the engine C by means of a chain connection trained over the multiple chain drive sprocket 24 secured to the shaft 22. Means are provided for effecting a forward and reverse drive between the drive shaft 22 and jackshaft 21, which means includes fixed sprockets 25 and 26 and a sprocket 27 journaled on the shaft 22 together with a gear 28 secured to the shaft 22. The gear 28 meshes with the gear 29 journaled on the shaft 21 and is adapted to be releasably clutched thereto by means of a clutch 30. The sprockets 25, 26 and 27 are aligned with companion sprockets 31, 32 and 33 mounted upon the jackshaft 21. The sprockets 31 and 32 are adapted to be selectively clutched to the jackshaft 21 by means of a common clutch member 34 adapted to selectively clutch either sprocket 31 or 32 to the shaft 21. The sprocket 33 is secured to the shaft 21.

A clutch 35 is provided for releasably clutching the high speed drive sprocket 27 to the drive shaft 22. The companion sprockets 26, 32, 25, 31 and their respective drive chains provide intermediate and low speed driving connections between

the shafts 22 and 21. Secured to the jackshaft 21 are the lineshaft high and low speed sprockets 36 and 37, respectively, which are aligned with companion multiple chain sprockets 38 and 39 mounted on the lineshaft 4.

A spline coupling member 40 is mounted upon the lineshaft 4 in position to engage selectively either sprocket 38 or 39 with the lineshaft 4. It will thus be apparent that the lineshaft 4 may be driven forwardly at any one of six selective speeds, and two speeds in reverse.

Low and high speed multiple chain sprockets 41 and 42 are journaled on the lineshaft 4 to align with the drumshaft sprockets 43 and 44 to effect the drives through the medium of chain connections. The sprocket 42 is releasably clutched to the lineshaft 4 through the medium of the high speed friction clutch 8 and the sprocket 41 is releasably coupled to the shaft 4 through the medium of a spline coupling 46. The sprocket 43 is journaled on the drumshaft 1 and is adapted to be releasably coupled to the drumshaft 1 through the medium of the low speed friction clutch 9.

The high speed friction clutch 8 may be of any suitable or desirable construction but is herein illustrated in Figure 6 as including a housing member 50 having a sleeve section 51 upon which the sprocket 42 is secured. The sleeve section 51 is journaled on spaced bearings 52 on the lineshaft 4. The housing member 50 carries the friction plates 53. A clutch spider 54 is secured to the shaft 4 and is provided with an axially immovable wall 55 and an intermediate disc 56 adapted to be brought into frictional engagement with the friction plates 53 through the medium of a movable clutch plate 57 to effect clutching of the sprocket 42 to the lineshaft 4.

Any suitable form of shifting mechanism as indicated at 58 may be employed for this operation controlled through the medium of a movable clutch collar 59 operated through the clutch shifter ring 60.

The spline coupling 46, utilized for releasably coupling the sprocket 41 to the lineshaft 4, may also be of any suitable or desirable construction, as, for example, illustrated in Figure 5. The purpose of this coupling 46 is to permit disengagement of the sprocket 41 from the lineshaft 4 in order to avoid driving the heavy duty transmission connection 3 during the long periods when the lineshaft 4 is turning to drive the rotary machine A.

The sprocket 41 is journaled on spaced bearings 61 upon the shaft 4 and is provided with a spline hub 62 over which an internally splined coupling collar 63 is adapted to be moved. The spline collar 63 has the elongated internal spline 64 adapted to mesh with the splines of the hub 62 and at the same time mesh with the external splines 65 of the coupling collar 66 which is secured to the shaft 4. The internally splined collar 63 is provided with a shifter ring annular recess 67 adapted to receive a shifter ring (not shown, but of any suitable or desirable type well understood in the art).

The low speed friction clutch 9 may be of any suitable or desirable type, as, for example, is illustrated in the co-pending application of Frank L. Gillett, Serial No. 381,476, filed March 3, 1941, issued December 8, 1942, Patent No. 2,304,350, and is provided to selectively connect the sprocket 43 in driving relation with the drumshaft 1.

The drumshaft coupling 10 may be of any suitable or desirable construction and is herein

illustrated as including the sleeve member 48 upon which the sprocket 44 is formed and which sleeve is journaled on spaced bearings 68 upon the drumshaft 1. Journaled on the sleeve 48 on spaced bearings 69 is a power take-off sprocket 49.

Secured to the end hub 70 of the power take-off sprocket 49 by means of drivers 71 is a driving ring 72. The driving ring 72 is provided with internal spline teeth 73 and a driving collar 74 secured to the shaft 1 is provided with external splines 75.

A selective drive spline collar 76 is provided with internal spline teeth 77 and external spline teeth 78. The internal spline teeth 77 engage complementary external splines on the reduced section 79 of the sleeve 48. The length of the spline 77 is such as to maintain the same at all times in engagement with the external splines of the reduced section 79 of the sleeve 48 to permit the coupling collar 76 to be moved to an intermediate position where the spline 77 is out of engagement with the spline teeth 75 and where the spline teeth 78 are out of engagement with the internal spline teeth 73 of the drive member 72 or to permit the selective engagement of either such pairs of drive splines.

A disconnecting self-aligning coupling 15 is provided between the fluid brake 16 and the driving collar 74 positioned on the end of the drumshaft 1. The fluid brake 16 is connected by the internal splines on coupling 15 to the drumshaft during the operation of lowering the drill string into the hole as will be well understood by those skilled in the art.

The cathead shaft 12 is supported upon the common frame structure 23 by means of spaced bearings 81. The opposite ends of the cathead shaft 12 carry the usual cathead 13 and an automatic cathead 83. A sprocket 84 is secured to the cathead shaft 12 and is driven through the medium of a chain from a cathead shaft drive sprocket 85 journaled on the lineshaft 4 and adapted to be releasably clutched thereto through the medium of a clutch member 86.

The friction clutches 8 and 9 are of the air operated types and the friction clutch 9 is used for all hoisting operations except those where the load is very light, as, for example, for the raising of the empty blocks or for the running of the rotary table. It is not practical to use the high friction clutch 8 to hoist any appreciable load since the speed ratio of the sprockets 42 and 44 is such as to produce a relatively high speed lift insufficient for transmission of the torque drive to the shaft 1 required for the normal hoisting operations.

In order to control the operative elements of the drawworks embodying my invention, control means are provided as diagrammatically illustrated in Figure 3. This control means is of the air actuating type for controlling the flow of air under pressure for operating the high and low speed clutches 8 and 9.

The control is had through treadles 87, 88 and 89 providing respectively for the operation of the drum 11 at high speed through operation of the high speed clutch 8 controlled by the treadle 87, operation of the low speed clutch 9 controlled by the treadle 88, and disconnection of the operation of the drum through the treadle 89. Treadles 90 and 91 are provided for controlling the operation of the power take-off sprocket 49. A selector lever 92 is provided for actuation through the suitable controls of the coupling 10.

Air under pressure from any suitable or desirable source is provided through a conduit 93 and is connected with the actuating cylinder 94 for the high speed clutch 8. The air under pressure from supply conduit 93 is also piped to drum control valve unit 95 and to power take-off control unit 96. Air lines 108 and 111 leading from unit 95 are connected to selector valve 97 and to air actuated friction clutch 9, respectively, while the air line 110 leading from unit 96 is connected only to the selector valve 97.

The selector lever 92 is connected by means of a link 98 with a bell-crank 99 which is pivotally supported upon a pin 100. One arm 101 of the bell crank 99 is connected to the shifter lever 102 for the shifter collar of the spline coupling 16. Movement of the selector lever 92 thus shifts the collar 16 axially of the drumshaft 1.

Connected to the arm 103 of the bell crank 99 through the medium of a link 104 is a crank arm 105 which in turn is secured to the plug 106 of the selector valve 97 so that actuation of the selector lever 92 determines the position of the plug 106. The plug 106 has the two positions indicated in Figures 3 and 4 wherein the multiple ports 107 thereof establish communication from the air pressure line 108 to the air line 109 to the cylinder 94 from the drum control unit 95 in one instance (Figure 3) or establish communication between air lines 110 and 109 leading from the power take-off control unit 96 to the high speed clutch actuating cylinder 94 in the other instance (Figure 4).

The control units 95 and 96 are in effect treadle actuated valve mechanisms for selectively controlling the flow of air to the low speed air actuated friction clutch 9, and to the power cylinder 94 for the high speed friction clutch 8. The control unit 95 includes a base 112 and supporting shafts 113 and 114 upon which shafts there are secured the actuating fingers 115 and 116. Secured to the shaft 113 is the high speed drum treadle 87. Secured to the shaft 114 is the low speed drum treadle 89.

Journalized between the shafts 113 and 114 is the neutral drum treadle 88. Carried by the base 112 is a pivot pin 117 on which is journalized a sleeve 118 carrying valve actuating arms 119 and 120. Each of the arms 119 and 120 carries a valve shifter finger 121 adapted to ride in grooves 122 formed in the valve collars 123. A spring-urged pawl 124 is carried by the base 112 adapted to engage in a series of detents 125 formed in the connecting web 126 of the fingers 119 and 120.

The intermediate treadle 88 is retained in position upon the ends of the shafts 113 and 114 by means of positioning collars 127, each of which is provided with an actuating lug 128 adapted to engage contacting lugs 129 of the treadle 88.

A stop plate 130 is formed on the base 112 to limit downward depression of the treadles. Supported in the base 112 are the control valves generally designated 131 and 132. The valve 131 controls the flow of air under pressure to the line 108 and the valve 132 controls the flow of air under pressure to the line 111. Valves 131 and 132 are a balanced type commercially obtainable, and each includes a shiftable sleeve 123 and a stationary tube 133. The tube 133 has a blind portion or central obstruction 134 in its axial bore, and on each side of this obstruction are a plurality of ports 135, 136 extending radially through the wall of the tube. The sleeve 123 may be shifted axially to cover both series of ports 135, 136, thereby establishing communication between

the pressure supply 93 and its respective outlet line 108 or 111. When the sleeves 123 are in the position shown in Figure 12, the exhaust ports 136 are open to atmosphere and the ports 135 are dead-ended into the recess within the sleeves 123. In operation depression of the low speed treadle 89 causes the arm 120 to shift the collar 123 to establish communication between the supply pipe 93 and the line 111, causing actuation of the low speed clutch 9.

The depression of the high speed treadle 87 acts similarly on valve 131 to admit air to the line 108 which, if the selector lever 92 is in position as illustrated in Figure 3, admits air to the high speed clutch cylinder 94, causing engagement of the clutch 8. Depression of the neutral or intermediate treadle 88 results in shutting off the flow of air into lines 108 and 110, and venting these lines to atmosphere through exhaust ports 136.

The power take-off control unit 96 is similar in construction to control unit 95 so that where applicable, the same numerals, with an exponent *a*, have been utilized to indicate a similar construction.

The valve 131^a is actuated to "open" position by the treadle 90 and to "closed" position by the treadle 91. Similar supporting shafts and actuating means are interposed between the treadles 90 and 91 and the valve 131^a and indicated by the same numerals.

In operation of this control, the selector lever 92 is actuated to engage the spline coupling 16 with the power take-off sprocket 44. The control valve 97 is shifted to the position indicated in Figure 4 to connect the line 110 to the line 109. Actuation of the "rotary in" treadle 90 then causes air under pressure to flow through the line 110, valve 97, through the line 109 into the cylinder 94 to cause engagement of the high speed friction clutch 8.

Actuation of the "rotary out" treadle 91 vents the line 110 to the atmosphere through exhaust ports 136^a, thereby causing the piston and the cylinder 94 to return and release the high speed friction clutch 8. It will be apparent from the foregoing that only one of the control units 95 and 96 may operate the high speed friction clutch 8 for any one setting of the selector lever 92.

When the selector lever is in the position which connected the spline coupling 16 with the drumshaft 1, the drum control unit 95 is the only one which will actuate the high speed friction clutch 8. Similarly, when the selector lever 92 is moved to position the coupling 16 to connect the power take-off sprocket 44, the power take-off control unit 96 alone will actuate the friction clutch 8. By this means inadvertent operation of the drumshaft or the power take-off is made improbable.

Having fully described my invention, it is to be understood that I do not wish to be limited to the details herein set forth, but my invention is of the full scope of the appended claims.

I claim:

1. In a rotary drawworks, the combination of a drumshaft assembly comprising a drum mounted on a drumshaft, a lineshaft, a driven element rotatably mounted coaxially of said drumshaft assembly, a power take-off element rotatably mounted coaxially of said drumshaft assembly, a transmission connection between said lineshaft and said driven element including a friction clutch on said lineshaft, a single positive coupling element adapted to engage said driven element

in driving relation with said drumshaft assembly, or to engage said driven element with said power take-off element, and means to actuate said lineshaft friction clutch for driving either the drumshaft assembly or the power take-off element as required.

2. In a rotary drilling rig including a draw-works having a lineshaft, a drumshaft, and a drum on the drumshaft, the combination of a sleeve rotatably mounted coaxially of the drumshaft, a driven element fixed on said sleeve, a releasable transmission connection between the lineshaft and the driven element including a friction clutch on the lineshaft, a hub fixed on said drumshaft adjacent said sleeve, a power take-off element rotatably mounted upon said sleeve between the driven element and the hub, and a single positive coupling element slidably axially of said drumshaft and adapted to place the driven element in direct driving relation with either the power take-off element or the hub.

3. In a rotary drilling rig including a draw-works having a lineshaft, a drumshaft, and a drum on the drumshaft, the combination of means whereby the lineshaft may drive the drum including a clutch on the drumshaft in driving relation with said drum, a driven element rotatably mounted coaxially of the drumshaft, means whereby the lineshaft may drive said driven element including a friction clutch on the lineshaft, a power take-off element rotatably mounted coaxially of the drumshaft, and a positive coupling element adapted at one time to remain in one position to connect the driven element with the drumshaft during the operation of going in the hole, and adapted at another time to remain in another position to connect the driven element with the power take-off element during the operation of coming out of the hole, whereby the required rotation of the drum and power take-off element incident to either operation may be accomplished solely by alternate actuation of said clutches, substantially as described.

4. In a rotary drilling rig, a drawworks having in combination a drumshaft assembly comprising a spooling drum mounted on a drumshaft, a lineshaft, a pair of rotatable members each rotatably mounted coaxially of the drumshaft assembly, drive means including a releasable friction clutch associated with the lineshaft whereby the lineshaft may rotate one of said members, power transmission connections operatively connecting the other of said members to drive a driven mechanism, positive coupling means selectively operable for connecting said members together to rotate as a unit or for connecting the first named member to the drumshaft assembly whereby the drive means may be selectively utilized for driving the driven mechanism or for rotating the drumshaft assembly, a shifter device for operating said positive coupling means, dual control means for operating said lineshaft friction clutch, and means responsive to actuation of said shifter device adapted to render one of said dual control means inoperative.

5. In a rotary drilling rig including a draw-works having a drum mounted upon a drumshaft, the combination of a driven element rotatably mounted coaxially of the drumshaft, a power transmission member, means including a friction clutch associated with said power transmission member adapted to rotate said driven element, a power take-off element rotatably mounted coaxially of the drumshaft, positive coupling means

selectively operable to place the driven element in driving relation with either the power take-off element or the drum, a power cylinder operable by fluid pressure for actuating said friction clutch, drum control means for admitting fluid pressure to said power cylinder, power take-off control means for admitting fluid pressure to said power cylinder, and means controlled by the position of said positive coupling means for rendering only one of said control means operative at any one time.

6. In a hoisting apparatus having in combination a spooling drum drive element, a power take-off drive element adapted to drive a rotary machine, a drive means including coupling means to selectively drive either of said elements, dual control means associated with said drive means, one of said control means being adapted to operate the drive means through the drum drive element, the other of said control means being adapted to operate the drive means through the power take-off drive element, and means to render the latter control means inoperative when driving the drum drive element.

7. In an apparatus of the character described, the combination of a spooling drum drive element, a power take-off drive element, drive means including a fluid pressure actuated clutch and positive releasable coupling means adapted to operatively drive either of said elements, actuating means to selectively actuate the positive coupling means, control valve means adapted to supply fluid pressure when driving one element, a second control valve means adapted to supply fluid pressure when driving the other element, selector valve means operatively connected with both control valve means and to said fluid pressure actuated clutch, and selector valve operating means responsive to the position of the actuating means for rendering either of said control valve means operative and the other inoperative.

8. In an apparatus of the character described, having in combination, a spooling drum drive element, a power take-off drive element, drive means including a releasable drive clutch and positive coupling means adapted to operatively drive either of said elements, actuating means to selectively actuate the positive coupling means, means to operate said drive clutch, said last named means including dual control means to selectively control the operation of said releasable clutch when driving either element, selector means operatively connected with said actuating means and responsive to the position of the actuating means for rendering either of said control means operative and the other inoperative.

9. In a well drilling apparatus, the combination of a spooling drum drive element, a power take-off drive element, drive means including a releasable drive clutch and selective coupling means adapted to operatively drive either of said elements, said coupling means adapted at one time to remain in operative driving relation with the spooling drum drive element during the operation of "going in the hole," and adapted at another time to remain in operative driving relation with the power take-off drive element during the operation of "coming out of the hole," means operatively associated with the selective coupling means and the drive clutch to control the driving of either element to the exclusion of the other, during the respective operations, through the drive clutch.

FORREST J. YOUNG.
